UNITED STATES PATENT OFFICE.

LE ROY E. JOLLS, OF DETROIT, MICHIGAN, ASSIGNOR TO PACKARD MOTOR CAR COMPANY, OF DETROIT, MICHIGAN, A CORPORATION OF MICHIGAN.

SLOTTING MACHINE.

Application filed May 3, 1918. Serial No. 233,310.

To all whom it may concern:

Be it known that I, LE ROY E. JOLLS, a citizen of the United States, and resident of Detroit, Wayne County, State of Michigan, have invented certain new and useful Improvements in Slotting Machines, of which the following is a specification.

This invention relates to slotting machines and particularly to machines for castellating nuts. The particular machine illustrated in this application is designed as an improvement upon the machine forming the subject matter of an application of Herbert S. Jones, Serial No. 232,834.

One of the objects of the present invention is to provide a rigid support and uniform driving mechanism for the cutters of a slotting machine.

Another object of the invention is to provide a more rigid work table support and operating mechanism.

Another object of the invention is to provide a novel work table lifting mechanism.

Another object of the invention is to provide a machine of the class referred to with a work ejecting means of novel form.

Another object of the invention is to provide novel and efficient work feeding and clamping mechanisms.

Other objects of the invention will appear from the following description taken in connection with the drawings, which form a part of this specification, and in which:

Fig. 1 is a side elevation of a machine embodying the invention, parts being broken away to show the internal construction;

Fig. 2 is a vertical section substantially on the line 2—2 of Fig. 1;

Fig. 3 is a plan view of the machine shown in Figs. 1 and 2;

Fig. 4 is a detail plan view of the work table and adjacent parts of the machine;

Fig. 5 is a detail sectional view of a nut clamping device;

Fig. 6 is an enlarged vertical sectional view showing the nut ejecting means;

Fig. 7 is a horizontal sectional view through the machine on the line 7—7 of Fig. 2;

Figs. 8, 9 and 10 illustrate three positions

of the various parts of the nut feeding mechanism;

Fig. 11 is an enlarged transverse section through the feeding magazine on the line 11—11 of Fig. 8; and

Fig. 12 is an enlarged underneath view of the nut feeding mechanism shown in Fig. 8, with parts broken away.

Referring to the drawings, 20 represents the base of the machine and 21 is a large hollow frame mounted upon the base and forming the principal support for the operating mechanism.

In the present form of the machine the movable work table is rotatably mounted and it is likewise adapted to be reciprocated to feed the work toward and from the cutters. The table proper is indicated at 22 and it is in the form of a cylindrical plate 70 horizontally arranged and having a central tapered trunnion 23 mounted for rotation in a table support 24. The latter has a central body portion 25 and an upper plate portion 26, the latter being arranged beneath the table 22 and having a filler block or plate 27 thereon arranged between its upper surface and the lower surface of the table 22. The support 24 is mounted in a part 24' of the frame of the machine so 80 that it may be reciprocated vertically therein, and a key 24'' prevents the support from turning about its axis. The table 22 is formed with a boss 28 which rests upon the upper face of the portion 26 of the support 85 24 and inside of the block 27, thus supporting the table 22 so that its under surface is either just out of contact with the upper surface of the block 27 or at least only lightly in contact therewith. This is for the purpose of permitting the table 22 to rotate 90 above the block 27 without undue friction thereon.

For castellating hexagon nuts as shown herein, the table 22 is formed with six nut receiving recesses 29 equally spaced near the periphery of the table, these recesses extending through the table so that nuts fed to them will rest upon the block or plate 27. The table is also provided at each of these 100 recesses with a nut clamping device such as shown in Fig. 5. This comprises a clamping

bolt 30 radially arranged just outside of the recess and having its inner end extended into such recess so that it may be brought into contact with a nut inserted in the recess. 5 A light spring 31 keeps the bolt 30 yieldingly in retracted position. This bolt and spring are arranged in a peripheral recess 32 in the table and a heavier spring 33 and an operating piece 34 are likewise retained 10 in the recess 32, as by a retaining nut 35. The piece 34 extends through the nut 35 and in normal position the bolt 30 is retracted from the recess. Surrounding the table 22 on the side where the 15 hereinafter described cutters are located is a cam 36, so positioned that its tapered end 37 (Fig. 3) contacts with the piece 34 and forces the latter inwardly so that the spring 33 overcomes the resistance of the spring 31 20 and presses the bolt 30 firmly in contact with the side of a nut N that has been previously inserted in the recess. This cam 36 retains the bolt 30 in clamped position throughout a part of the rotation of the table 22 or until 25 the particular piece 34 has passed the other end 38 of said cam, when the clamping device automatically unclamps.

The table 22 is intermittently rotated by the well known Geneva movement comprising 30 a star plate 39 having six radial slots 40, an arc shaped surface 41 between them, and an arm 42 having a pin 43 adapted to operate in the slots 40 and a cylindrical plate 44 adapted to operate against the arc shaped 35 surface 41 and having a cut-out portion 45 permitting unlocking action while the pin 43 rotates the plate 39 through one-sixth of a revolution. This movement is well known and is clearly shown in Figs. 1, 2 and 7, and 40 no further description is thought necessary. The plate 39 is secured to the lower projecting end of the trunnion 23 of the table 22 as by the nuts 46, and the arm 42 and plate 44 are keyed or otherwise secured upon a shaft 47 arranged parallel to the axis of the 45 table 22. The pin 43 is made long enough and the periphery of the plate 44 is of sufficient width to permit the required amount of reciprocation of the plate 39 with the 50 table 22 as will be hereinafter described.

The table 22 is reciprocated for feeding by means of a cam 48 mounted upon the shaft 47 above referred to and having a cam groove 49 which co-operates with a pin 50 55 on the side of the table support 24. This cam groove 49 is formed to give the required lift to the table and it will be seen that there is a positive action both rising and falling and the entire table support and the table are 60 lifted for this feeding operation.

The connection of the cam 48 to the vertical shaft 47 is best shown in Fig. 2 where it will be seen that the shaft 47 is supported in a sleeve 51 which is adjustably mounted in 65 a collar 52 forming part of the frame 21 of

the machine. This collar has a detachable annular piece 53 secured to it as by screws 54 and a ring 55 is loosely clamped between the collar 52 and the piece 53 and around the sleeve 51. The ring 55 is connected to the sleeve 51 by a threaded connection so that upon rotating the ring 55 the sleeve 51 is raised or lowered in the collar 52. At the upper end of the sleeve 51 is a ball thrust bearing 56, shown in dotted lines in Fig. 2, 70 and the cam 48 which is keyed to the upper end of the shaft 47 as shown at 57 rests upon this thrust bearing 56 so that the cam is adjusted axially with the axial movement of the sleeve 51 and carries with it the shaft 47 75 the upper end of which is mounted in a bearing 47' formed in the frame of the machine. This axial adjustment is obtained manually by turning a cross shaft 58 having a worm 59 in mesh with worm gear teeth 60 formed 80 on the periphery of the ring 55. This axial adjustment of the cam 48 of course carries with it the table support 24 and consequently the table 22, thus adjusting the upper limit of travel of the latter in its feeding movement. 85

The cam 48 is provided with a worm gear 61 by which it is rotated from a worm 62 on a transverse shaft 63 mounted in suitable bearings in the frame of the machine. By 90 this arrangement the rotation of the cam 48 is in direct timed rotation with the rotation of the table 22 because of the fact that the table rotating mechanism comprising the Geneva movement is operated by the shaft 100 47 which moves with the cam 48. Thus the cam 48 makes one complete revolution for each one-sixth of a revolution of the table so that there is a complete up and down feeding movement of the table for each 105 period of rest from rotation thereof.

At the right of the machine as shown in Fig. 2, the frame 21 thereof extends upwardly somewhat above the line of the table 22 and supports the cutter mechanism. As 110 shown, there are three cutters or saws 64, 65 and 66 mounted on parallel shafts 67, 68 and 69 respectively, each of which is mounted in a pair of separated roller bearings 70 and 71 as shown in section in Fig. 2. 115 Each of the shafts also has a worm gear 72 arranged between the bearings and a driving shaft 73 is mounted in suitable bearings in the frame directly beneath the gear 72. This shaft 73 has worm teeth 74 in mesh with the gear 72, this arrangement being shown in Fig. 2 and in dotted lines in Fig. 1, and the shaft 73 is directly driven by a pulley 75 operating through a clutch mechanism 76. The outer end of the shaft 73 is supported in a bearing 77 in an arm 78 extending out 120 from the frame 21.

The upper extension of the frame 21 which supports the cutter mechanism fully encloses the cutter shafts and is formed with 130

an oil reservoir 79 above the shaft 73 and oil holes 80 lead from this reservoir directly to the gears 72. A cover 81 is provided for the reservoir and a needle valve 82 is provided

5 for each of the openings 80 so that the feed of oil to the gears can be regulated. There is also an oil conduit 83 formed in the frame of the machine from the lower part of the housing of the shaft 73 and extending to the 10 bearing 47' for the shaft 47 so that excess oil fed to the gears 72 and 74 will run down into the bearing 47' and on to the gears 61 and 62 and the cam 48 so that those parts are also properly lubricated.

15 For the purpose of driving the shaft 63 and consequently rotating and reciprocating the work table, a train of gears is provided from the shaft 73 to the shaft 63, at one side of the machine, as shown at 84, 85 and 86 in 20 Fig. 1, the gear 84 being on the shaft 73 and the gear 86 being on the shaft 63.

It will be understood that the cutters 64, 25 65 and 66 are arranged to operate in parallel planes and are removed from each other sixty degrees circumferentially of the table. This is so that each of the cutters will cut one slot at a time in the nuts that are 30 respectively presented to them and the three slots so cut will be sixty degrees apart on the nuts.

The nuts are automatically fed to the machine by means of the feeding device shown in Figs. 8 to 11 inclusive and this device is supported from the frame of the machine 35 by an arm 87. It comprises a magazine 88 of tubular form and arranged directly over one of the recesses of the work table on the opposite side of the table from where the cutters are located. The magazine 88 is 40 preferably made of an outer cylindrical tube and an inner tube formed in two pieces split longitudinally to facilitate machining the hexagon interior. This construction is illustrated particularly in Fig. 11 where the

45 outer tube is shown at 89 and the two-piece inner tube at 90. These inner and outer tubes are preferably pinned together so that they are in effect one tube.

The magazine 88 is mounted for longitudinal reciprocation in a sleeve 91 which is 50 likewise mounted for longitudinal reciprocation to a limited extent in the arm 87 above referred to. The sleeve 91 has a transverse pin 92 operating in a slot 93 formed 55 in the side of the magazine 88 to limit the relative movement of its two parts, and the arm 87 has a transverse pin 94 operating in a slot 95 formed in the side of the sleeve 91 to limit the relative movement between 60 those parts. A cover plate 96 on the upper part of the arm 87 and surrounding the magazine 88 forms an abutment for two springs 97 and 98, the former of which has 65 its lower end resting against a collar 99 secured to the magazine 88 as by the screw

100, and the latter of which, that is the spring 98, has its lower end bearing against the sleeve 91. Thus the springs 97 and 98 yieldingly retain the magazine 88 and the sleeve 91 in their lower extreme positions. 70

The lower part of the sleeve 91 is contracted somewhat where it surrounds the lower end of the magazine, and a second sleeve 101 is arranged on this lower part of the sleeve 91 and adapted to slide longitudinally thereon. This sleeve 101 is yieldingly retained in its lowest position by a spring 102 arranged between a shoulder 103 on the sleeve 101 and a shoulder 104 on the sleeve 91. The sleeve 101 is shown as formed of two parts for convenience of manufacture but it will be understood that the outer part 105 and the inner part 106 always move together. A pin 107 in the sleeve 101 extends into a slot 108 in the lower extension of the 80 sleeve 91 to limit the relative movement of the two sleeves. An underneath view of the magazine and the surrounding sleeves is shown in Fig. 12 and the pin and slot 107 and 108 are also shown therein by cutting 85 away parts of the sleeves.

Referring to said Fig. 12, as well as Figs. 8, 9 and 10, it will be seen that the end of the magazine 88 is formed with a slot 109 in which a holding dog 110 is pivoted as at 111. 95 This dog extends through a slot 112 in the lower end of the sleeve 91 and has a finger 113 operating in a slot 114 which terminates in an inclined surface 115. The dog 110 also has another finger 116 which is adapted to 100 be operated upon by a second inclined surface 117 in the sleeve 101. These two inclined surfaces 115 and 117 are so positioned that they will positively rock the dog 110 on its pivot as the sleeve 101 is reciprocated relatively to the magazine 88. The dog 110 has a toe 110' which is adapted to catch under the nuts N in the magazine as shown particularly in Fig. 8.

There are also three pusher dogs 118 110 pivoted as at 119 in slots 120 in the lower part of the sleeve 91. These dogs are equally spaced around the sleeve and as they are all alike the operation of only one of them will be described. Each of the 115 dogs 118 has a toe 121 which operates through a slot 122 formed in the lower end of the magazine 88 and as this dog is pivoted slightly above the dog 110 its toe 121 catches under the second nut in the magazine 120 instead of under the first nut. The dog 118 has a finger 123 and a heel 124 which are adapted to operate in a slot 125 having inclined surfaces 126 and 127 respectively, in the sleeve 101. 125

The operation of the nut feeding device is as follows: In Fig. 8 the table 22 and its support 24 are in retracted position, the table being slightly below the bottom of the sleeve 101 of the feeding mechanism. In 130

this position of the parts the toe 110' of the dog 110 is under the lowest nut N thereby retaining the nuts in the magazine. The dog is held in its position by reason of its finger 116 being against the interior surface of the sleeve 101. The dog 118 has its heel 124 in the slot 125 so that the dog is retracted.

In Fig. 9 the table has been moved upwardly into contact with the sleeve 101 and has pressed the latter upwardly relatively to the sleeve 91 and the magazine, the spring 102 being lighter than either of the springs 97 and 98 so that the latter two springs hold the magazine and the sleeve 91 in their lower positions. This relative movement of the sleeve 101 on the magazine and sleeve 91 causes a change in position of the dogs 110 and 118. The former is turned on its pivot to release the lowest nut in the magazine as shown in said Fig. 9 and the dog 118 is turned on its pivot so that its toe 121 is moved in under the second nut in the magazine thereby retaining all but one of the nuts therein.

In Fig. 10 the table has reached the full upper limit of its stroke and the upper end of the sleeve 101 has been pushed against the shoulder 104 on the sleeve 91, and the table is in contact with the lower end of the magazine itself so that the sleeve 101, the magazine 88, and the sleeve 91 have all been moved upwardly against the action of the springs 97 and 98. However, as the lower end of the magazine was in contact with the table in the position shown in Fig. 9, the continued movement of the table moved the magazine relatively to the sleeve 91 until the sleeve 101 reached the shoulder 104, and this relative movement caused the three dogs 118 to move downwardly relatively to the magazine and push the first nut in the magazine which had been released by the dog 110 down into the recess 29 in the table. This position of the parts is shown in Fig. 10 and after the relative movement of the magazine and the sleeve 91 had ceased by reason of the sleeve 101 abutting against the shoulder 104, all of the parts moved upwardly together to the upward limit of movement of the table.

In the reverse operation the dog 118 releases the nuts which have been held by their toes 121 and the nuts are caught by the toe 110' of the dog 110 which has again been brought into operative position. The complete operation is then repeated with each reciprocation of the work table.

The work table 22 rotates in the direction of the arrow 128 in Fig. 1 and the nut feeding magazine 88 therefor is located at some point ahead of the cutters or saws. After the nuts have passed the saws and been operated upon they are released by the cam 36 and in most cases would drop

through an opening 129 formed in the part 26 of the support 24. It is found in practice, however, that the nuts will sometimes stick in the recess due to chips getting into the recesses, and for the purpose of positively ejecting the nuts from the recesses and cleaning the recesses of chips an ejecting mechanism is provided. This consists of a hollow pin 130 supported by an arm 131 over the opening 129 where the finished nut rests during one reciprocation of the table. The arm 131 is rigidly mounted upon the frame 21 of the machine as by the bolts 132, and the pin 130 is connected by a flexible pipe 133 with a pump 134 which may be operated from some moving part of the machine such as by the shaft 135 connected to the shaft 73 hereinabove described. The pump 134 is suitably connected with a source of oil supply so that it will constantly pump a stream of oil through the pin 130 and upon the table 22.

The operation of this device is as follows: When the finished nut reaches a position on the table over the opening 129, if it is caught in the recess it will sometimes be freed by the action of the stream of oil issuing from the hollow pin 130. However, if this does not free the nut, the reciprocation of the table 22 will bring the nut against the lower end of the pin 130 and the nut will be positively pushed through the recess 29 and through the opening 129, where it falls from the machine through the shoot 136. From this shoot the nuts are led to a suitable receptacle.

Having thus described my invention, what I claim and desire to secure by Letters Patent is:

1. In a slotting machine, in combination with a reciprocating work table, means to effect a series of progressive operations upon the work by the reciprocation of said table, a member having a cam groove engaging a part connected to said table for positively reciprocating the table both to and from the cutter, and means for operating said cam groove member.

2. In a slotting machine, in combination, a reciprocating table support, a work table thereon, a cam arranged at one side of the table support and connected to positively move the table both to and from the cutter, means for performing successive operations upon the work by said reciprocation, and means for operating the cam.

3. In a slotting machine, in combination, a work table mounted for reciprocation and rotation about an axis, a series of cutters arranged for successive operation upon the work as the table rotates, a table support, a cam arranged at one side of the table support and connected to reciprocate it, and means for rotating the table and cam.

4. In a slotting machine, in combination,

2 a support, a work table mounted on said support, a cam arranged at one side of the table support and connected to positively reciprocate it, means for rotating the table, 5 means for operating the cam, and means for performing successive operations upon the work during said reciprocation.

3 5. In a slotting machine, in combination, a vertically reciprocable member, a work 10 table rotatably supported at one end of said member and having a part extending through said member, means at the other end of said member for rotating said work table, and means connected to said member 15 intermediate its end for reciprocating it.

4 6. In a slotting machine, in combination, a cutter, a movable work table, a cam connected to move the table, means for operating the cam, and means for adjusting the 20 cam relative to said operating means to change the relation of the table to the cutter.

5 7. In a slotting machine, in combination, a cutter, a work table movable toward and 25 from the cutter, a cam connected to move the table and rotatably supported means for adjusting the support for said cam to change the relation between the table and cutter, and means for operating the cam.

6 8. In a slotting machine, in combination, 30 a cutter, a vertically reciprocating work table, a support for said table, a rotary cam supported at one side of said support and connected to move the table, means for vertically adjusting the support for said cam to change the limit of throw of the table and means for rotating the cam.

7 9. In a slotting machine, in combination, 40 a cutter, a vertically reciprocating work table, a support for said table, a rotary cam supported at one side of said support and connected to move the table, means for vertically adjusting the support for said cam to change the limit of throw of the table and 45 relative to the cutter and means coaxial with said adjusting means for rotating the cam.

8 10. In a slotting machine, in combination, 50 a cutter, a vertically reciprocating work table, a support for said table, a rotary cam supported at one side of said table support and connected to reciprocate the latter, means for adjusting the cam support parallel to the table movement to change the throw of the table relative to the cutter, and 55 means keyed to the cam for rotating the latter.

9 11. In a slotting machine, in combination, 60 a movable work support, a cutter for operating on the work in one position of said support, and means for projecting a stream of liquid against the work in another position of said support, a nozzle positioned to contact with and positively eject the work in the movement of the work support.

10 12. In a slotting machine, in combination,

a vertically reciprocable and rotatable work table, a series of rotary saws disposed to cut successive slots in the work, spindles for said saws lying in the same horizontal plane, a fixed support for said spindles, worms for 70 driving said spindles, and a common worm shaft for said worms.

13. In a slotting machine, in combination, a support, a vertically movable and rotatable work table mounted thereon, a series of rotary saws mounted adjacent the table and on spindles in fixed supporting means, a cam for moving said work table mounted on a vertical axis and fixed against vertical movement, worm gearing for operating said cam, 80 worm gearing for operating said spindles, and gearing between said worm gearings.

14. In a slotting machine, in combination, a support, a vertically movable and rotatable work table mounted thereon, a series of saws 85 mounted adjacent the table and on spindles in said support, a cam for moving said work table, parallel shafts connected for operating said spindles and cam respectively, and gearing connecting said shafts.

15. In a slotting machine, in combination, a reciprocable and non-rotatable table support, a work table rotatably mounted on said support, rotary cam means connecting with the side of said support for reciprocating 95 said support and the table thereon, and means for rotating the work table.

16. In a slotting machine, in combination, a support, a vertically reciprocable work table mounted thereon to rotate about a vertical axis, a series of three saws on three 100 separate but parallel spindles above the table and lying in the same horizontal plane and sixty degrees apart relative to the axis of said table, a fixed support for said saw spindles, means for operating said spindles, and gearing from said spindles for operating said table.

17. In a slotting machine, in combination, a reciprocable and non-rotatable table support, a work table rotatably mounted on said support, rotary cam means connecting with the side of said support for reciprocating 110 said support and the table thereon, and means for intermittently rotating the work table in time with the reciprocations.

18. In a slotting machine, in combination, a vertically reciprocable and non-rotatable table support, a work table rotatably mounted thereon and having a part extending through said support, means for reciprocating said support and table, and means operating on said extended part of the table 120 for rotating it.

19. In a slotting machine, in combination, 125 a support, a work table mounted thereon for horizontal rotation and vertical reciprocation, a rotating vertical spindle mounted in the support adjacent the table, cam means between said spindle and table for recipro-

cating the latter, Geneva mechanism between said spindle and table, saws and spindles therefor mounted in the support above the table, a driving shaft, gearing from said shaft to said saw spindles, and gearing from said shaft to said vertical spindle.

20. In a slotting machine, in combination, a rotary work table having a series of work receiving seats, a work clamp for each seat, and a stationary cam adjacent said table adapted to operate said clamp and hold it in clamping position throughout a portion of the rotation of said table.

21. In a slotting machine, in combination, a rotary work table having a series of work receiving seats, a work clamp for each seat, a spring for said clamp and a stationary cam adjacent the table to operate said clamp.

22. In a slotting machine, in combination, a rotary work table having a series of work receiving seats, a work clamp for each seat and having a part extending beyond the periphery of the table, a spring for said clamp and a stationary cam arranged adjacent the periphery of the table and adapted to contact with said part and operate said clamp.

23. In a slotting machine, in combination, a work table, a blank magazine, blank retaining means and means operated by the table to release said retaining means for feeding a blank to the table.

24. In a blank feeding device, in combi-

nation, a support, a magazine yieldingly held therein, a sleeve at the delivery end of said magazine, and dogs operated by said sleeve to feed the blanks singly.

25. In a blank feeding device, in combination, a support, a holder slidably mounted in said support, a magazine slidably mounted in said holder, a sleeve slidable on said holder, and dogs operated by said sleeve to feed the blanks from the magazine.

26. In a blank feeding device, in combination, a support, a holder slidably mounted in said support, a magazine slidably mounted in said holder, a sleeve slidable on said holder, a dog supported by the magazine, and a dog supported by the holder, said dogs being operated by said sleeve to feed the blanks from the magazine.

27. In a slotting machine, in combination, a vertically reciprocable table support, means preventing rotation of said table support, a work table rotatably mounted on said table support, a rotatable cam mounted with its axis parallel to the axis of said work table, means for rotating said cam, means connecting said cam and table support whereby the rotation of the cam reciprocates the table support, and means connected to rotate said work table relatively to the table support.

In testimony whereof I affix my signature.
LE ROY E. JOLLS.
